MULTIFORM PRINTING MACHINE

Junior A. B. Peak and Frank Kautzman,
Salt Lake City, Utah

Application June 29, 1940, Serial No. 343,298

5 Claims. (Cl. 101—277)

The object of our invention is to provide a multiform printing machine using a new type of action whereby a single form of type may be used for making a multiplicity of impressions while the paper remains on the cylinder; and to particularly provide means for a delayed action of the table of the printing machine relative to the cylinder, whereby a single form of type can make impressions upon different sections of paper without taking same from the printing cylinder, thereby eliminating hand or automatic feeding of the stock through the press more than once.

We attain these and other objects of our invention by the mechanism illustrated in the accompanying drawings, in which—

Figure 1 is a top plan view of the invention with parts shown in section and a portion of the machine broken away;

Fig. 2 is a vertical section on line 2—2 of Fig. 3;

Fig. 3 is a longitudinal vertical section through the machine on line 3—3 of Fig. 2 with a portion of the machine broken away;

Fig. 4 is a detail sectional view of adjustable cams;

Fig. 5 is a detail sectional view through a portion of the cams with means for adjusting said cams shown in elevation;

Fig. 6 is a diagrammatic view of the table and cylinder while in the act of printing the first impression on the paper;

Fig. 7 is a diagrammatic view of the table and cylinder while in the act of printing the second impression on another section of the paper;

Fig. 8 is a diagrammatic view of the table and cylinder while in the step of printing a third impression on a third section of the paper; and,

Fig. 9 is a plan view of a sheet of paper showing the relation of the three impressions.

Like characters of reference designate like parts in each of the several views.

Referring to the accompanying drawings, we provide a main frame 1, on which is mounted a drum or impression cylinder 2, supported by a drum shaft 3, which is mounted in drum shaft bearings 5, as shown in Fig. 2. The drum shaft 3 is driven by a drum sprocket 4, which is connected by a drive chain 7, or other equivalent means such as gears, with the sprocket 6 on jack shaft 8. Jack shaft 8 at its inner end carries bevel pinion 9. A bevel gear 10 on a cam shaft 11 is driven by the bevel pinion 9 and in turn drives the cam shaft 11. The jack shaft 8 is mounted in bearings 12 and 14, as shown in Fig. 2. The sprocket jack shaft 8 is driven by a sprocket 55

13 and chain 13a from sprocket 13b on the motor shaft of a suitable motor M.

Referring to Figs. 1 to 5 inclusive, we provide an adjustable cam 15, an adjustable cam 16 beneath the cam 15, and cam 17 beneath the cam 16, the cam 17 being keyed to shaft 11 and rotatable therewith, as shown in the drawings. A cam follower 18, as shown in Fig. 3, engages the edge of the cams. We provide a cam adjusting screw 19 having a threaded engagement with an adjusting screw nut 20, an adjusting screw stop 21, and an adjusting screw nut 22. Adjusting screw nut 20 is mounted on intermediate cam 16. Adjusting screw nut 22 is mounted on upper cam 15 and adjusting screw stop 21 is mounted in bottom cam 17. We provide end springs 24, each having one end secured at 25 to the main frame 1 and having the other ends of said springs secured at 25' to the carriage frame 29. Or any other suitable and equivalent means may be used in place of springs 24 for return of the carriage frame 29 to its original position.

Referring to Figs. 1, 3 and 4, a cam locking screw 26 passes through the elongated adjusting slots 28 in cams 15 and 16 and is secured to the bottom cam 17. Cam locking screw 26 carries a knurled nut 27 for manual adjustment.

A carriage frame 29 carries spaced rollers 30 which ride on the carriage rails 31, as shown in Fig. 2. On opposite sides of the machine a lower pinion rack 33 is affixed to rail 31 and an upper pinion rack 34 is affixed to a type bed table 35. Like light differential pinions 32, supported by carriage 29, mesh with the lower pinion racks 33 and with the upper pinion racks 34. Type bed table 35 rides on rollers 30 and carries the type bed 36 and type 37. As shown in Fig. 2, opposite longitudinally grooved carriage guides 38 receive and guide the ends or hubs of the carriage rollers 30; the opposite table guides 39 guide the type bed table 35.

As shown in Fig. 2, paper discharge cam 40 is attached to an upper cam guide 41 and to a lower cam guide 42. Paper grip fingers 43 are mounted on a shaft 44, supported by the ends of impression cylinder 3, as shown in Fig. 3. Cam 40 operatively engages a cam 40' on gear 45a. A cam gear shaft 45 carries the cam gear 45a, which meshes with the gear 45b which is mounted on the drum shaft 3. The upper cam guide 41 is mounted in a bearing 46. On the other end of upper cam guide 41 is a collar 47 which holds the upper spring 48 in place. Similarly on the outer

end of cam guide 42 is a collar 49 which holds the lower spring 50 in place.

As shown in Figs. 2 and 3, a cam follower arm 51 carries a cam follower 52 which rollably engages the paper discharge cam 40.

As shown in Fig. 3, a sheet 53 to be printed is carried by the drum 2 to receive a series of printing impressions from the type 37 on successive portions of the sheet, such as those designated No. 1, No. 2, and No. 3 in Fig. 9.

In operation, the motor M from motor sprocket 13b, drives the jack shaft 8 by suitable means such as chain 13a and sprocket 13. Jack shaft 8 carries a sprocket 6 which drives a chain 7 and a sprocket 4 on a drum shaft 3 on which a drum or impression cylinder 2 is affixed. Drum shaft 3 also carries cam follower arm 51, which in turn carries the cam follower 52. The jack shaft 8 also carries a bevel pinion 9, which drives bevel gear 10 attached to cam shaft 11, and thereby rotates the cams 15, 16, and 17, which are mounted on the upper end of cam shaft 11.

Top cam 15 and intermediate cam 16 are adjustable relative to bottom cam 17 by means of the slots 28 and cam locking screw 26 extending through said slots and the nut 27.

The cams 15, 16, and 17 are made adjustable to provide for variations in the width of the sheets to be printed. The lobes of cams 15, 16, and 17 are designed to operate the cam follower arm 18 which in turn operates carriage 29 and the members operatively connected with carriage 29 to cause a delayed action of the type bed table 35 and its type bed 36 and type 37 to cooperate with successive portions of the drum or impression cylinder at each revolution of same. Inasmuch as the sheets of paper to be printed must be retained on the drum for a predetermined number of revolutions (three in the form of the invention illustrated), the members 40 to 51 hereinbefore described, provide for gripping of the paper prior to the printing and for releasing it after the final impression on the sheet.

Any suitable conventional mechanism may be utilized for feeding the paper to the drum and taking it off of the drum. Any conventional type can be applied to the press.

The cams 15, 16 and 17 are rotated by the shaft 11 and successively their edges operatively contact with the cam follower 18, as shown in Fig. 3, thereby operating the carriage 29 with a reciprocatory horizontal movement. As the carriage 29 is moved rearwardly its differential pinions 32 ride in the lower pinion racks 33 and also mesh with the upper pinion racks 34 which are attached to the type bed table 35, thereby moving the type bed table 35 and its type bed 36 and type 37 with a horizontal reciprocatory movement in the direction in which the carriage 29 moves.

As the type bed table 35, type bed 36 and type 37 travel beneath the cylinder, a first impression is made on the portion of sheet 53 designated "No. 1" (see Figs. 6 and 9). After the table has traveled beneath the cylinder, it is returned to its position while the drum or printing cylinder 2 carrying sheet 53 is revolving. During this revolution of the cylinder, one of the cams 15, 16, or 17 causes a delay or retardation of the forward action of the table so as to bring another portion of section of sheet 53 (see Figs. 7 and 9) into position for the second impression on sheet 53 at the portion designated "No. 2." This operation is repeated the third time, the delayed action bringing still another section or segment of sheet 53

into position above the type 37 for a third impression on sheet 53 on the portion designated "No. 3" (see Figs. 8 and 9). After this operation the sheet 53 is removed from the drum 2 by conventional means, and a new sheet inserted.

While only three impressions on a sheet are illustrated and described, the device might be made for printing any suitable number of impressions on a sheet by providing an appropriate or desired number of cams for causing delayed actions of the carriage frame and type bed table for each impression to be printed on the sheet. It is apparent that by use of such mechanism a single form of type can make an indefinite number of impressions on different sections of a sheet of paper without taking same from the printing cylinder. This will reduce the hand or automatic feeding of stock through the press and greatly expedite printing.

As illustrated in Figs. 4 and 5, the relative position of cams 15, 16 and 17 may be readily adjusted by means of screws 23 and 26 for longitudinal and lateral adjustment respectively.

As shown in Fig. 3 a series of paper grip fingers 43 mounted on shaft 44 grip the forward edge of the sheet to be printed and at the appropriate time release it. Paper discharge cam 40 operating as shown in Fig. 2, controls the cam follower arm 51 and causes the latter at the proper time to actuate the paper grip fingers 43 to release the forward edge of sheet 53 to discharge same from the drum after all the sections of the sheet have been printed. The cam 40 is normally held in contact with the ends of bearings 46 by the tension of springs 48 and 50, thereby holding it disengaged from arm 51 and leaving arm 51 in a nonoperative position. The rotation of cam member 40 moves cam 40 toward the drum 2, where it is engaged by cam follower 52 and thereby actuates member 51, which in turn releases the paper finger grips 43 from their engagement with the forward edge of the paper sheet 53 to discharge same from the drum.

What we claim is:

1. In a multiform printing machine, a rotary impression cylinder, paper finger grips releasably holding the forward edge of a sheet of paper on the cylinder, cam operated mechanism carried by the cylinder for releasing said paper finger grips from the paper to discharge the paper after making the last of a series of impressions on the sheet, a reciprocably movable type bed table carrying a type bed and type, means tending to operate the type bed table in one direction, a plurality of overlying horizontally disposed rotatable cams and arranged to operate it in a reverse direction and to delay its return movement to bring it into operative relation to the cylinder at successive portions thereof, and means for laterally adjusting and varying the size of the cam mechanism to modify its operation, whereby successive impressions may be made from the same type upon successive sections of a sheet of paper carried by the cylinder.

2. In a multiform printing machine, a rotary impression cylinder, means carried by said cylinder for releasably engaging the forward edge of a sheet of paper while a series of impressions are being printed on it, means for discharging it after the final impression, a reciprocably movable type bed table carrying a type bed and type, means tending to operate the type bed table in one direction, cam mechanism arranged to operate it in a reverse direction and to delay its return movement to a position

tion in operative relation to the cylinder to engage the cylinder at successive portions thereof for making successive impressions from the same type upon successive sections of a sheet of paper carried by the cylinder, said cam mechanism comprising a series of rotatable overlying cams projecting to a variable extent in a horizontal direction, and means operatively connected with each of the cam elements to adjust their position relative to each other to provide for variations in the width of the sheets to be printed, a cam follower in contact with the edge of said cams and operated thereby, a carriage to which the cam follower is attached, and means operatively connecting the carriage with the type bed table.

3. In combination with the machine defined in claim 2, the last-mentioned means comprising a rack attached to rails, the rails being fixed relative to the carriage, a reversely disposed rack attached to the type bed table, and pinions supported by the carriage and meshing with said racks.

4. In combination with the machine defined in claim 2, said last-mentioned means comprising racks attached to opposite sides of rails, the rails being fixed relative to the carriage, reversely disposed racks attached to the type bed table, and pinions meshing with the racks to cause movement of the type bed table, the pinions being supported by the carriage.

5. In combination with the machine defined in claim 2, said last-mentioned means comprising racks attached to opposite sides of rails, the rails being fixed relative to the carriage, similar racks reversely disposed and affixed to the type bed table, pinions supported by the carriage and meshing with the racks to cause movement of the type bed table, and means for simultaneously actuating the cam mechanism, the rotary cylinder and the mechanism for discharging the paper from the cylinder after the last of a series of impressions has been made on the sheet of paper carried by the cylinder.

JUNIOR A. B. PEAK.
FRANK KAUTZMAN.
